UNITED STATES PATENT OFFICE.

SOLOMON K. MEYERHOFF, OF PHILADELPHIA, PENNSYLVANIA.

SHIRT.

SPECIFICATION forming part of Letters Patent No. 562,636, dated June 23, 1896.

Application filed February 24, 1896. Serial No. 580,514. (No model.)

To all whom it may concern:

Be it known that I, SOLOMON K. MEYERHOFF, a citizen of the United States, residing in Philadelphia, Pennsylvania, have invented 5 certain Improvements in a Combined Shirt and Tie, of which the following is a specification.

The object of my invention is to so combine a necktie with a shirt that it will form a permanent part of the shirt and can be washed with it. The necktie is so arranged that the shirt can be opened in front without disturbing the tie.

My invention is especially applicable to 15 negligée shirts made of washable material, and I prefer to make the tie of the same material and of the same pattern as the shirt, but the tie may be made of a different pattern and may in some instances be made of other material.

In the accompanying drawings, Figure 1 is a front view of sufficient of a shirt to illustrate my invention, the tie being unfastened. Fig. 2 is a similar view showing the tie fastened. Fig. 3 is a sectional plan view on the line 3 3, Fig. 2. Fig. 4 is a sectional perspective view. Fig. 5 is a view of a form in which the loop is permanent. Figs. 6 and 7 are views of other modifications.

30 The shirt shown in the drawings is an open-front shirt and the tie is on the outer flap A. The inner flap A' is made in the ordinary manner and simply has a button a, to which the outer flap can be secured, and in this outer flap is a buttonhole a' for this purpose.

As shown in Fig. 1, the band B, which forms the bow of the tie, is an extension of the neckband of the shirt and is of a sufficient length to form the two bows, as shown in Fig. 2. The 40 loop is formed by a short section D, extending from the upper edge of the neckband, and, as shown in Fig. 1, this section has a button-hole d, adapted to a button a² on the lower portion of the neckband, so that when the shirt is put on the wearer first buttons the neckband, then turns the section D over, buttoning it to the button a², forming the loop of the tie. Then the free end of the section B is passed through the loop to form the right-hand bow x and returned to form the left-

hand bow x', the end of the portion B resting within the bow x, as shown in Fig. 2. Thus the tie is formed, which resembles the ordinary looped tie.

By simply releasing the outer flap from the 55 button a the shirt-front can be opened and the shirt removed without undoing the tie.

In Fig. 5 I have shown the section D of the tie permanently in the form of a loop, being fastened at the top and bottom to the band, 60 the section B forming the bow being made in the manner shown in Fig. 1. In this view, Fig. 5, I have shown the tie made of material having a different design from that of the shirt.

In some instances I may extend the neckband of the outer flap A' to form a tip independent of the section B, Fig. 6, said tip having a buttonhole, so that the shirt can be closed without interfering with the tie, the buttonhole a' in the section B being dispensed with. The buttonhole may be arranged also directly back of the loop-section and this loop-section D may be attached to the button which fastens the two neckbands together, as shown in Fig. 7, without departing 70 from my invention.

My invention is as applicable to a shirt with a stand-up collar as to one having a lay-down collar, as shown.

I claim as my invention—

1. As a new article of manufacture, an open-front shirt, provided with a section B forming a continuation of the neckband and having a loop attached thereto at the neckband through which the said continuation is 85 passed back and forth to form the bow of a tie, substantially as described.

2. As a new article of manufacture, an open-front shirt, provided with a section B forming a continuation of the outer flap of 90 the shirt and having a section D extending from the upper edge of the neckband, with means for securing the end of said section D to the lower edge of the neckband to form a loop through which the continuation B is 95 passed back and forth to form the bow of a tie, substantially as described.

3. As a new article of manufacture, an open-front shirt provided with a section B forming a continuation of the neckband of 100

the outer flap of the shirt, said section having a buttonhole a' by which the outer flap is secured to the neckband of the inner flap of the shirt, and a section D forming a loop through which the section B is passed back and forth to form the bow of a tie, substantially as described.

In testimony whereof I have signed my name to this specification in the presence of two subscribing witnesses.

SOLOMON K. MEYERHOFF.
